UNITED STATES PATENT OFFICE

ARTHUR THOMAS, OF THORNTON HEATH, ENGLAND, ASSIGNOR TO THE ACCOUNTING & TABULATING CORPORATION OF GT. BRITAIN LIMITED, OF LONDON, ENGLAND

CARD PERFORATING MACHINE OR THE LIKE

Original application filed January 10, 1930, Serial No. 419,974, and in Great Britain January 21, 1929.
Divided and this application filed March 25, 1931. Serial No. 525,254.

This invention which is a division of my application, Serial No. 419,974, filed January 10th, 1930, relates to card perforating machines or the like, and has for its object to 5 provide means whereby the carriage may be moved back one step and at the same time the individual latch for the column of set bars corresponding to the position of the carriage after it has thus moved is released.

10 In the type of machine to which the invention relates, the carriage carries a plurality of setting members in the form of plungers which are arranged in one column from front to rear of the machine, the setting members 15 corresponding to and being controlled by the keys e. g. through the agency of Bowden mechanism and bell crank levers, so that on depression of the respective key the setting member is depressed.

20 The column of setting members so carried by the carriage is traversed step by step over a field of set bars of which there are a plurality of columns producing lines of bars at right angles to each column, the number of 25 columns being at least as great as the number of columns formed on statistical cards, sheets or the like, to be perforated in the machine, each column comprising a set of bars one corresponding to each setting member.

30 As the carriage is traversed over the field the columns of setting members are brought successively over each column in the field of bars. Upon the depression of one of the setting members the respective bar in the col-

35 umn of the bars under the setting members at the particular position of the carriage, is depressed, and is held depressed by a spring pressed latch bar which engages with a shoulder on the depressed bar.

40 In moving down, the bar depresses a spring pin. There is one such pin for every bar and the springs on these pins tend to keep the pins in upward position, which is their normal position, the springs also serving to 45 reset the respective bars when the latch aforesaid has released them.

Each of the latch bars has its front end arranged in juxtaposition with a pivoted releasing pawl formed with an oblique face 50 hereafter referred to.

Beneath the spring pins the punches are arranged one punch for each pin in a stripper plate, and the lower ends of the punches extend into a movable frame comprising a die and die plate between which is a space, for 55 the introduction of the cards to be perforated.

This frame is reciprocated vertically under power and when a card is in the space between the die and die plate, the card is moved up with the frame and encounters all the 60 punches, lifting them with it.

If a spring pin is depressed it attempts to stop the upward movement of the respective punch, but as the respective bar is held by the latch aforesaid the spring pin acts as an 65 abutment for the punch and causes a corresponding perforation of the card.

In the operation of such a machine the key board is operated to actuate one or more of the setting members at each position of the 70 carriage and at the end of the carriage traverse of the field of bars the punch key is operated, thereby connecting the frame to power which effects the perforation of the card according to the setting action. 75

In the drawings Fig. 1 is a perspective view of a punch perforating machine embodying the invention.

Fig. 2 is a front elevation of the machine.

Fig. 3 is an end elevation looking from the left of Fig. 2.

Fig. 4 is a section on the line IV—IV of Fig. 2 but with the release bar actuating mechanism in elevation.

Fig. 5 illustrates on an enlarged scale the back-spacing mechanism and the means for resetting one individual column of set bars, and

Fig. 6 shows a detail of the arrangement shown in Fig. 5. 90

In the construction illustrated the carriage 1 has attached thereto a cable 2 passing over a jockey pulley 3, the other end of the cable being anchored to a wheel 4, the construction of which will be described later. The jockey pulley 3 lies in a loop 2a of the cable and is carried on an arm 5 pivoted at 5a to the frame of the machine the weight of the pulley tending to cause the arm to assume a substantially horizontal position when the car-

riage is in its initial position as stated above. The carriage is advanced step by step when the keys are pressed, by means of a spring within a housing 1a.

- 5 Mounted on the machine frame is a toothed wheel 6 geared to a pinion 7 connected to one of the pinions 8 of the feed mechanism for the cards, sheets or the like, the toothed wheel 6 constituting the rotatable member serving 10 to operate the carriage return mechanism, and on one face of the toothed wheel 6 is a roll 9 which acts as the abutment on the pivoted lever 5 which is coaxial with the pinion 7 aforesaid.
- 15 On the depression of the punch key 10 at the end of a setting operation a Bowden cable 11 moves a lever 12 about its pivot 13. The upper end of this lever is turned over at 14 and provided with an oblique slot 15 engaging 20 with a pin 16 carried on a bar 17. Owing to the obliquity of the slot 15 movement of the lever 12 causes an axial movement of the bar 17 which allows a spring pressed plunger 17a to engage with a member 18 provided 25 with dog teeth so as to connect an electric motor 19 through a gear train 19a, 19b, 19c, to the pinion and the toothed wheel 6 causing the roll to press down the lever 5 during its rotation to the substantially horizontal 30 position, when the carriage is returned. The plunger 17a is automatically disengaged from the teeth of the member 18 by means of a cam 35 number 18b over the surface of which the plunger rides and is then withdrawn from engagement with the dog teeth after one revolution of the member 18. The bar 17 is returned to its initial position by the spring 18a.

The arrangement is such that the roll 9 starts its operation on the pivoted lever 5 with a minimum speed so that the initial movement of the carriage 1 is of gradual nature, the speed of which is accelerated up to the middle of the movement and then decelerated until the end of the movement, that is to say, there is what may be termed a simple harmonic motion in operation with the lever 5.

The wheel 4 to which the cable 2 is attached is provided with a spring 20 having one end secured to the wheel at 20a and the other to the machine frame at 20b (see Fig. 3). The wheel 4 carries a stop 21 adapted to engage with a fixed abutment 22 when the carriage is in its initial position.

In Fig. 3 the carriage has moved from this position so that the arm 5 is not horizontal. In the event of the punch key being depressed whilst the carriage for some reason or other is prevented from moving with the cable, the wheel 4 is rotated and the spring 20 becomes stressed, the stop 21 on the wheel being retracted from the abutment 22 on the frame to the desired extent, and then automatically returned under the spring action.

The spring on the wheel aforesaid also acts 65 as a guard for the operator, and is especially

useful when the carriage is returned over a part only of its traverse as in gang punching, as the arrest of the carriage does not interfere with the working of the pivoted lever.

Referring now to the pivoted release pawls arranged at the front end of each of the latch bars as hereinbefore referred to as comprised in a perforating machine for cards, sheets or the like, there is pivotally mounted on the escapement wheel shaft of the carriage carrying the setting members, a rocking member adapted to be operated by hand provided with an arm connected by a link to a rocking lever usually disposed just above the latches and mounted on the carriage frame and carrying at its free end a bevelled roller.

When the rocking member is operated by hand it is rocked so as to move the roller downwardly on to the oblique or cam faces of the latches through the agency of the link and secend rocking lever hereinbefore referred to. If then the carriage is returned towards the left of the machine the roller passes over the oblique or cam faces of all the latches and causes them to move their respective latch bars longitudinally thereby releasing all the bars previously set and which were previously locked by the latching bar.

In such form of machine after a setting operation the punch key is operated and then the carriage returned to the left hand or starting position with the result that all the release pawls are operated and the latch bars caused to release the set bars.

Now in a construction according to the present invention it is preferred to modify the means of releasing the latches.

To this end there is provided in operable relation with all of the release pawls or latches 27 a release bar 28 arranged transversely of them, and operable laterally to simultaneously return all latch pawls to normal position, whereby they cause the movement of the latch bars to release any set bars.

The operation of this release bar 28 may be automatic or by hand, and in the hand operation there is provided a lever 30 at one side of the machine which can be moved manually into the chain line position in Figure 4 in which a nose 30a on the lever causes a lateral displacement of the bar 28. For the purpose of releasing individual latches there is provided as in the known constructions a rocking member 31 pivotally mounted on the shaft 32 of the escapement wheel 33.

Mounted to slide axially on the rocking member 31 is a plate 34 provided at one end with an arm 35 connected by a link 36 to a rocking lever 37 which carries instead of a pivoted roller a finger 38 so that on the operation of the rock member 31 the finger operates on particular latch which is determined by the back spacing mechanism now about to be described. This back spacing mechanism

is conveniently combined with the escape-
ment mechanism and may be employed
whether or not the modified arrangement for
operating the release pawls is employed.
5 The back spacing mechanism includes a back
spacing pawl 39 formed on the sliding plate
34 and adapted to engage with the carriage
rack 40 when the member 31 is rocked. The
member 31 is provided with a hand lever 41
10 and when this lever is brought into the posi-
tion shown in chain lines in Fig. 5 the pawl
39 engages with the rack 40 and the carriage
is moved back one tooth of the rack as per-
mitted by the slots 31a in the member 31.
15 Simultaneously the finger 38 is operated to
reset the column of bars corresponding to the
new position of the carriage.

By such an arrangement if an error has
been made in punching a hole in a particular
20 column, the carriage can be returned to the
column and the latch bar released by one
movement of the back spacer lever and the
bars reset by operating the correct key.

Referring now to the operation of the
25 latches 27 by a power operated release bar 28
arranged transversely of them, as employed
in a machine having means for automatically
returning the carriage 1 to initial position as
hereinbefore described, the movement of the
30 bar 28 may be effected on the return of the
carriage 1 by carrying the bar on arms 42
mounted on a rock shaft 43 operable from
the source of power.

Conveniently the tooth wheel 6 operating
25 the pivoted lever 5 of the return mechanism
for the carriage 1, the arrangement being
synchronized so that when the carriage has
returned, the setting latches have all been re-
leased and the machine is immediately ready
40 for the next punching operation.

One of the pivoted arms 42 mounted on
the rock shaft 43 heretofore mentioned for
operating the release bar 28 conveniently
45 forms the bearing for the hand lever 30 for
operating the bar independently of the rock
shaft and the rock shaft is also mounted for
axial adjustment so as to disengage it from
the source of power when it is required to op-
erate it by hand. To this end one end of the
50 rock shaft 43 is provided with a head 44 un-
der which passes a push rod 45 having a cam
surface 46 which engages the head and on
being pushed causes the axial displacement
by a camming action.

55 At the other end of the rock shaft is fixed
an arm 47 which on the displacement of the
rock shaft is carried out of the path of an
actuating member 48 carried by the tooth
wheel 6 aforesaid of the carriage return
60 mechanism.

On such operation the release bar 28 can
be operated by hand.

On the retraction of the push member 45
effecting a cam action on the rock shaft 43,
65 the latter is preferably spring returned to

bring its arm 47 into the path of the actuating
member or roll 48 on the tooth wheel 6,
so that the latch bar 28 is power operated
synchronously with the return of the carriage
as hereinbefore explained.

Should it be desired to put any of the
latches 27 out of operation for the time being
the bar 28 may be raised by means of the lever
30 having its nose 30a engaging with the bar
28 (Figs. 3 and 4). The lever 30 is normally
70 held in the full line position by a spring 30b
but is depressed into the dotted position to
raise the bar 28 clear of the latches. Any
latch may then be pulled out into the position
75 shown at 27a where it is out of action. The
bar 28 may then be lowered to prevent the
remaining latches from coming out.

By the present invention, a perforating
machine is provided whether or not there is
20 a carriage return mechanism with improved
means of actuating the release pawls by hand
or by power whereby corrections can be
effected in a column if an error has been
made by depression of the wrong key, and in
25 the combination of the actuating mechanism
for the release pawls with the carriage return
mechanism, apparatus is provided in which
the release pawls are actuated to release the
latch bars synchronously with the return of
30 the carriage although at will the actuation of
the release latches may be withheld when it
is desired to do repetition work.

It may here also be mentioned that in a
machine provided with a back spacing device
35 the carriage travel is increased to the extent
of one column so that in the end position of
the carriage the operation of the back spacing
mechanism will bring the carriage setting
levers over the end column of bars for the
40 correction of that column as may be desired.

An advantage arising out of this construc-
tion is that the operation of the keys in the
45 end position of the carriage cannot produce
an incorrect setting of the bars in the end
column as does occur in an ordinary machine
when the carriage at the end of its traverse
is over the end column. In that case, if the
50 operator, believing there is one more column
to go, operates another key, this causes the re-
setting of the bars in the end column, conse-
quently the setting of the wrong bar in the
55 end column.

By constructions according to the present
invention such errors are eliminated.

Although the mechanism herein referred to
has been described in its application to a
perforating machine for cards, sheets or the
like, the description is by way of example
only, as the invention is applicable to any
form of record making devices in which a
60 carriage is traversed during a series of setting
operations and the record effected by a sepa-
rate key or actuator.

What I claim is:—

In a punch perforating machine the com- 130

bination of a carriage, an escapement wheel shaft mounted on said carriage, a manually operable rocking member pivotally mounted on said shaft, a plate adapted to slide axially on said rocking member, an arm secured to said plate, a rocking lever, a finger carried on said lever and adapted to engage with and move an individual latch, an operative connection between said arm and said rocking lever, a rack for the carriage and a back spacing pawl formed on one end of said sliding plate, and adapted to engage with the rack, whereby when the rocking member is operated the said pawl is caused to engage with the rack and move the carriage backward one step, while at the same time the finger resets the column of setting bars corresponding to the position of the carriage after it has thus moved back.

20. In testimony whereof I affix my signature.

ARTHUR THOMAS.
